UNITED STATES PATENT OFFICE

EUGENE C. HERTHEL AND THOMAS DE COLON TIFFT, OF CHICAGO, ILLINOIS, ASSIGNEES
TO SINCLAIR REFINING COMPANY, OF NEW YORK, N. Y., A CORPORATION OF MAINE

ART OF CRACKING HYDROCARBON OILS

Application filed June 7, 1928. Serial No. 283,516.

This invention relates to improvements in the cracking of higher boiling hydrocarbon oils, such as gas oil, to produce therefrom lower boiling hydrocarbon oils, such as gasoline. This application is in part a continuation of an application filed June 22, 1926, Serial No. 117,697, which has matured into Patent No. 1,677,773.

This invention relates particularly to improvements in operations in which hydrocarbon oils are cracked by distillation under pressure and in which residual oil withdrawn undistilled from the pressure distillation is expanded at a lower pressure for the further separation of oil constituents as vapors therefrom. The invention has several important advantages in heat economies, in features of control, and in the maintenance of conditions which permit prolongation of the useful period of operation without sacrifice of efficiency.

In carrying out the present invention, the oil to be cracked is subjected to distillation under pressure at a cracking temperature in a pressure still. The vapors driven off from the still are subjected to a refluxing operation in a reflux tower from which reflux is returned to the still, and the vapors remaining uncondensed from the refluxing operation are condensed to form the distillate product. The operation is carried out in a continuous manner by supplying fresh oil to the pressure still charge and withdrawing unvaporized oil containing the pitch formed by cracking during the operation. The pitch laden oil withdrawn from the still charge is expanded by reducing the pressure thereon and is thereby separated into an unvaporized residue and an oil fraction driven off as vapors. The pitch content of the unvaporized oil withdrawn from the pressure still charge is separated in this residue and the oil components of the withdrawn material, or the greater part of them, are separated as vapors, this separation advantageously being effected simply by the heat contained in the pitch laden oil from the pressure still. In accordance with the present invention, the oil vapors separated from the pitch laden oil withdrawn from the pressure still are passed

through a tower through which fresh oil to be supplied to the pressure still is passed in indirect heat exchanging relation with these vapors. This fresh oil is thus heated and the vapors cooled. The heavier components of the vapors are condensed and the condensate is introduced while hot directly into the pressure still. Lighter constituents such as those suitable as components of the distillate product remain uncondensed and are withdrawn and separately condensed. The thus heated fresh oil is then introduced into the reflux tower through which the vapors from the pressure still are passed. To control or assist in controlling the refluxing action in the tower through which the vapors separated from the unvaporized oil withdrawn from the pressure still are passed, part of the fresh oil may be by-passed around this tower. To control or assist in controlling the refluxing action in the tower through which the vapors driven off from the pressure still are passed, the fresh oil heated by heat exchange with the vapors in the other tower may be partially cooled before introduction into the pressure still reflux tower, or as before additional fresh oil may be introduced into the pressure still reflux tower. Further to control or assist in controlling the reflux action in either or both of the towers, a part of the distillate product or some similar light fraction may be introduced into the vapors in the towers. Light fractions so supplied to either or both of the towers are substantially completely revaporized, escaping with the vapors from the tower to be condensed therewith. Additional fresh oil may also be supplied directly to the pressure still charge, if necessary, for example to maintain the still charge.

Fig. 1 of the accompanying drawings is a pictorial representation of the operation of the process of the invention. The invention will be further described in connection with Fig. 2 of the drawings which illustrates in a diagrammatic and conventional manner, an apparatus adapted for carrying out the process of the invention.

Referring to Fig. 2 of the drawings, the pressure still illustrated comprises a bulk

supply tank 3 located away from the heating furnace 4, a battery of vertical heating tubes 5 arranged in the heating furnace and circulating connections 6, 7 and 8 and a circulating pump 9 arranged to withdraw oil from the bulk supply tank and force it upwardly through the heating tubes and back to the bulk supply tank. Vapors from the bulk supply tank escape through connection 10 and pass upwardly through reflux tower 11, uncondensed vapors escaping from the upper end of the reflux tower through connection 12 to the condenser 13 in which they are condensed, the condensate collecting in receiver 14. A connection 15 is provided for discharging the uncondensed vapors and gases and a connection 16 for the discharge of the condensate. Reflux, and admixed unvaporized fresh oil introduced into the reflux tower, are returned from the reflux tower 11 to the circulating line connecting the bulk supply tank with the suction side of the circulating pump through connection 17. Unvaporized oil is withdrawn from the bulk supply tank 3 through connection 18 arranged to discharge into expander 19. The pressure releasing valve 20 is provided in connection 18, advantageously at a point adjacent the pressure still, to control and reduce the pressure between the bulk supply tank and the expander. To promote vaporization, steam, or other hot gaseous medium, may be introduced into the expander 19, for example, steam may be injected into and admixed with the oil as it enters the expander. As little as one percent of steam will, in many cases, materially increase the amount of vaporization over any particular pressure drop. To inhibit entrainment, several baffles are arranged in the upper end of expander 19. Vapors escape from the expander through connection 21 and unvaporized material is discharged through connection 22. The vapors from the expander pass upwardly through the expander reflux tower 24, uncondensed vapors escaping from the upper end of this tower through connection 25 to condenser 26 in which they are condensed, the condensate collecting in receiver 27 which is provided with a discharge connection 28 for uncondensed vapors and gases and a connection 29 for the discharge of condensate. Fresh oil is forced through coil 23 acting as a heat exchanger arranged within the tower 24 and then introduced into the upper end of tower 11 through connections 31, 32, 33 and 35 by means of pump 30. The fresh oil flowing through connections 32 and 33 may be passed in whole or in part through cooler 36. Fresh oil may also be supplied by means of pump 30 to the upper end of the reflux tower 11 through connections 31, 37 and 35. The condensate collecting in the lower end of expander reflux tower 24 is withdrawn through connection 34 and returned directly to the

pressure still through connection 38 by means of pump 39. As a supplemental refluxing or condensing agent or controlling medium, a part of the distillate product can be re-introduced either into the upper end of the reflux tower 11 through connection 40 or into the upper end of expander tower 24 through connection 41. The hot parts of the apparatus as well as the hot connections are advantageously lagged or heat insulated to prevent heat loss, particularly the expander 19. Cool oil for cooling and lubricating the bearings of the circulating pump 9 is supplied through connection 42. Cool fresh oil in excess of the amount required to cool and lubricate the pump bearings may also be supplied to the pressure still charge through this connection. Additional fresh oil may also be supplied to the pressure still charge through connection 43.

In operation, the pressure still is charged with fresh oil and brought to cracking conditions of temperature and pressure. In a still of the type illustrated, an initial charge of about 8000 gallons of cold oil, that is oil at a temperature of about 80° F. for example, is commonly employed. The pressure maintained during the operation is determined to a large measure by the stocks to be treated and the products to be obtained. With gas oil character charging stocks, pressure up to 125 lbs. per square inch or more may be used, and with charging stocks containing large amounts of kerosene character components, much higher pressure, say up to 300 lbs. per square inch may be used. When the still is brought to operating conditions fresh oil is initially introduced through connections 31, 37 and 35 and pressure distillate vapors are discharged into the condenser and condensed, the pressure being regulated by valve 44 between the reflux tower and the condenser. The pressure may also be regulated if desired by valves beyond the condenser. During the initial period of operation, unvaporized oil is not withdrawn from the pressure still, or is withdrawn in but small amount, but before the pitch concentration in the charge of oil in the pressure still reaches an objectionable value, the withdrawal of pitch laden oil in substantial amount is begun. The pitch laden oil withdrawn is discharged into the expander 19 where a pressure substantially lower than that prevailing within the pressure still is maintained, the pressure between the still and the expander being reduced by means of valve 20. Due to this reduction in pressure, the withdrawn pitch laden oil is subjected to further vaporization, the vapors entering the expander tower and pitch components separating in a residue remaining unvaporized. The degree of vaporization in the expander can be controlled by regulating the pressure therein. As much as 80% or more of the pitch laden oil may be so va-

porized by its self-contained heat, but if a liquid residue is to be obtained, it is usually not desirable to go much beyond this point and it may be necessary to reduce the amount of vaporization, although a liquid residue can sometimes be obtained with vaporization of as much as 90% of the pitch laden oil. Or if desired, the expander can be run to separate a coke or cokey residue in which event a series of the expanders becomes necessary so that the operation can be carried out continuously. With still pressures in the neighborhood of 100 lbs. per square inch or more, the pressure in the expander may be maintained at a value between atmospheric pressure and say 50 lbs. per square inch or more, depending upon the amount of vaporization desired. When the withdrawal of pitch laden oil is begun, and vapors from this oil begin to pass through the expander tower, the fresh oil is passed through coil 23 on its way to the reflux tower 11. For purposes of control, part of the fresh oil supplied to the reflux tower 11 may still be passed through connection 37 instead of through coil 23 and connections 32 and 33. Fresh oil is passed through coil 23 and heated by heat exchange with the vapors in tower 24, or part of it may also be passed for purposes of control through cooler 36 on its way to reflux tower 11. Operating for the production of gasoline or gasoline containing pressure distillate with a gas oil character charging stock, as an example of the operation of the invention, the temperature at the top of the reflux tower 11 may be maintained at about 550° F. and the temperature at the top of expander tower 24 at about 350° F. The pressure distillate may be taken off at a rate, for example, of about 1000 gallons per hour and pitch laden unvaporized oil withdrawn from the still charge at a rate of about 1500 gallons per hour, requiring the return to the pressure still of 2500 gallons of oil per hour to maintain the charge. The temperature of the oil as withdrawn from the pressure still, during operation under a pressure in the neighborhood of 100-125 lbs. per square inch, may approximate 700-725° F., and on reduction to approximately atmospheric pressure up to about 80% or 1200 gallons per hour of this oil may be vaporized. The temperature of the vapors and of the residue escaping from the expander approximates 650° F. or upwards. Since part of this vaporized fraction of the oil withdrawn from the still charge escapes as vapors from the expander reflux tower, fresh oil in amount upwards of 1300 gallons per hour is supplied. When all of this fresh oil is passed through the heat exchange coil 23 in the expander reflux tower, the temperature of the condensate collecting in the bottom of the expander tower may approximate 400° F. or upwards. To maintain adequate refluxing action in the pressure still reflux tower 11 it is usually desirable to limit the temperature of the fresh oil introduced through connection 35 to a value not exceeding about 275-280° F. unless some supplemental refluxing agent is employed. If no fresh oil is supplied through connection 37 or if the fresh oil supplied through connection 37 is insufficient in amount to bring the oil mixture flowing through connection 35, including the heated fresh oil supplied through connection 33, within the desired temperature limit, the fresh oil flowing through connection 32 is partially cooled, so far as necessary, by means of cooler 36. The supply of oil to the pressure still reflux tower 11 is regulated with respect to the temperature of the oil to maintain the desired head temperature. If any additional fresh oil is required to maintain the still charge, it is supplied to the still charge directly. The condensate from the lower end of the expander reflux tower 24 is advantageously returned to the pressure still charge at as high a temperature as is available. To maintain the desired head temperatures, part of the distillate product may be supplied to the upper ends of the pressure still reflux tower and the expander reflux tower as required.

It will thus be seen that this invention provides an improved method of carrying out pressure distillation processes for cracking hydrocarbon oils which effects several heat economies. The separation of unvaporized oil withdrawn from the pressure distillation into a residue containing all of the pitch constituents of the withdrawn oil and a completely vaporized fraction is effected without requiring additional heat and further at least a part of the heat of the fraction so vaporized is returned to the pressure distillation in a particularly advantageous way. This heat is absorbed in fresh oil which is brought in heat exchanging relation with the vapors forming this separated fraction, and is thus returned to the pressure still in the heated fresh oil, as well as any condensate produced from these vapors. Part of this heat may be given off in cooling the fresh oil, but nevertheless some of it is returned and made usefully available in the cracking operation whereas otherwise it would be lost for this purpose. Heat so returned to the pressure distillation assists in prolonging the period over which the operation can be continued as it reduces to a corresponding extent the amount of heat necessary to be transferred through the walls of the pressure still in which the operation is carried out making possible lower furnace temperatures to effect any given conversion of a particular stock. Such lower furnace temperatures can be maintained efficiently by recycling part of the hot gases again over the heat transferring walls. With the withdrawal of substantial amounts of pitch laden oil from the pressure

distillation, the economy thus effected becomes particularly important. In carrying out the invention, lighter constituents present in the oil withdrawn from the pressure distillation which if returned might be subjected to over-cracking, are separated before the condensate produced from the vapors separated from this oil under reduced pressure is returned to the pressure distillation and may be combined with the distillate product. The invention has another advantage in that the apparatus for cooling the components of the pitch laden oil, in accordance with the invention, can be made compact and of a type easily maintained.

We claim:-

1. In processes of cracking higher boiling hydrocarbon oils to produce lower boiling hydrocarbon oils by distillation under pressure at cracking temperatures in which unvaporized oil is withdrawn during the pressure distillation and subjected to further vaporization by its self-contained heat under a reduced pressure, the improvement which comprises passing the vapors from the pressure still into a reflux tower, passing the vapors separated from the oil withdrawn from the pressure still into another reflux tower, passing fresh oil in indirect heat exchanging relation with the vapors in the second mentioned reflux tower and thereby subjecting the vapors to condensation and then introducing this fresh oil into direct contact with the vapors in the first mentioned reflux tower, returning reflux together with admixed unvaporized fresh oil from the first mentioned reflux tower to the pressure still and separately returning condensate from the second mentioned reflux tower directly to the pressure still.
2. In processes of cracking higher boiling hydrocarbon oils to produce lower boiling hydrocarbon oils by distillation under pressure at cracking temperatures in which unvaporized oil is withdrawn during the pressure distillation and subjected to further vaporization by its self-contained heat under a reduced pressure, the improvement which comprises passing the vapors from the pressure still into a reflux tower, passing the vapors separated from the oil withdrawn from the pressure still into another reflux tower, passing fresh oil in indirect heat exchanging relation with the vapors in the second mentioned reflux tower and thereby subjecting the vapors to condensation and then introducing this fresh oil into direct contact with the vapors in the first mentioned reflux tower, supplying additional fresh oil directly to the pressure still, returning reflux together with admixed unvaporized fresh oil from the first mentioned reflux tower to the pressure still and separately returning condensate from the second mentioned reflux tower directly to the pressure still.

3. In processes of cracking higher boiling hydrocarbon oils to produce lower boiling hydrocarbon oils by distillation under pressure at cracking temperatures in which unvaporized oil is withdrawn during the pressure distillation and subjected to further vaporization by its self-contained heat under a reduced pressure, the improvement which comprises passing the vapors from the pressure still into a reflux tower, passing the vapors separated from the oil withdrawn from the pressure still into another reflux tower, passing fresh oil in indirect heat exchanging relation with the vapors in the second mentioned reflux tower and thereby subjecting the vapors to condensation, partially cooling this fresh oil after this heat exchange, and then introducing this fresh oil into direct contact with the vapors in the first mentioned reflux tower, returning reflux together with admixed unvaporized fresh oil from the first mentioned reflux tower to the pressure still and separately returning condensate from the second mentioned reflux tower directly to the pressure still.

In testimony whereof we affix our signatures.
